United States Patent Office

Des. 203,412
Patented Jan. 4, 1966

203,412

FASTENER

George S. Wing, Palos Verdes Estates, Calif., assignor to
Hi-Shear Corporation, Torrance, Calif., a corporation
of California

Filed Oct. 6, 1964, Ser. No. 82,057

Term of patent 14 years

(Cl. D54—9)

FIG. 1

FIG. 2

FIG. 3

FIG. 1 is a partial view in perspective of a fastener showing my new design;

FIG. 2 is a right-hand view of FIG. 1; and

FIG. 3 is a side view of FIG. 2 with portions omitted to indicate indeterminate length.

The dominant features of my design reside in the portions shown in full lines.

I claim:

The ornamental design for a fastener, as shown and described.
